Attorneys.

Patented Nov. 30, 1926.

UNITED STATES PATENT OFFICE.

JOSEPH ROY, OF CLEVELAND, OHIO, ASSIGNOR TO AMERICAN STOVE COMPANY, OF ST. LOUIS, MISSOURI, A CORPORATION OF NEW JERSEY.

CONCEALED BASE FOR GAS RANGES.

Application filed June 30, 1926. Serial No. 119,662.

This invention relates to improvements in concealed base for gas ranges and it relates to a construction in which there is a base portion, side and front walls and a leg, all of them being connected by the same means.

The primary object of this invention is to so construct the parts that the base portion is substantially wholly concealed from the outside of the range.

10 A further object of the present invention is to form a base that is L shaped in cross section, the horizontal portion of the L extending outward and to form on the lower edges and side walls inwardly extending 15 horizontal flanges that rest on the outwardly extending horizontal flange of the base, the parts being secured together.

20 A further object of the invention is to construct a base portion that is L shaped in cross section, the horizontal portion of the L extending outward and to have the side and front walls with inwardly extending flanges, and in addition to connect a plate below the 25 horizontal wall of the base, this plate being constructed to fit in a recess formed in the top of the leg, all the parts being secured by bolts passing therethrough and into the said leg portion.

Further objects of the present invention 30 is to form a base that is L shaped in cross section having the horizontal flange of the L extending outwardly and the lower edges of the front and side walls extending inwardly and resting on top of the horizontal 35 wall of the base, and to strengthen all of these parts by a strengthening plate located beneath all of the plates, and into which suitable securing bolts pass.

Further objects of the present invention 40 will appear from the following description.

In the accompanying drawings:

Figure 1 is a perspective view of the lower front edge of the range construction and its supporting leg.

45 Figure 2 is a small view of that part of the base member that when completed is bent into a right angle.

Figure 2^b is a view of the same member as that shown in Figure 2^a except that it 50 shows the base after it is bent and the metal is stretched.

Figure 2 is a horizontal section on line 2-2 of Figure 1, looking upward.

Figure 3 is a horizontal sectional view on line 3-3 of Figure 1, looking downward. 55

Figure 4 is a perspective view of the base portion, the lower corners of the front and side walls and the brace plate, said parts being shown in detached relation.

Figure 5 is a perspective view of the upper end of the range leg looking downward thereon.

Figure 6 is a vertical sectional view on line 6-6 of Figure 3, looking in the direction indicated by arrows. 65

Figure 7 is a vertical sectional view on line 7-7 of Figure 3, looking in the direction indicated by arrows.

In carrying out this invention the base member is composed of a strip of metal 70 which is L shaped in cross section. This member is composed of an outwardly extending horizontal leg portion 1 and a vertically extending leg portion 2 that is located at the inner end of the horizontal portion. 75 This base portion is formed of metal, and the same is bent into angular form corresponding to the form of the range. It will be observed that the base portion A is bent into angular form that corresponds with 80 the angular form of the range. This is accomplished by cutting out of the horizontal flange 1 an angular opening 3. After this angular portion is cut out and the metal a which lies in the walls of the angular opening 3, is stretched it cuts the vertical leg 2 to the desired angle. This portion A forms a reinforcement flange whereby the base is strengthened at its corners. It will be understood that the whole part of the horizontal flange 1 of the base could be removed and the whole strengthening member would 85 depend upon the vertical member 2. By leaving the wall a as here shown then the base is very much strengthened. That is to say 90 after it has once been bent, then the reinforcement flange a serves to stiffen and hold it to its bent shape. Of course in stretching the metal a it is at its outer edge somewhat reduced in thickness, though the reduction 100 would be difficult to show in a drawing except if the drawing was made on a very large scale.

Having thus formed the base member A 105 into a shape corresponding to that of the range, the front wall 4 has its lower wall

- turned inward as shown at 5 and this bent-in portion preferably rests on top of the horizontal leg 1 of the base A. Also the outer edge of the front wall 4 is bent rearwardly as shown at 6 (Figure 3). The side wall 7 has its lower edge 8 also bent inward and rests upon the horizontal leg 1 of the base A. The said parts in this position are provided with registering openings 9 through which screws 10 pass. These parts are united by what is aptly referred to as brace plate 11, which also has openings 12 that register with the said openings 9. Attention is specifically called to the fact that the openings 12 in the brace plate 11 are threaded and that the threads on the bolts engage with the plates in the said openings. The upper ends or heads 13 of the screws are made in convenient form for the reception of a screw driver or other implement by means of which the screw can be turned and thus secure the lower edges of the side and front walls and the horizontal portion 1 of the base A to this brace plate 11.
- For further strengthening the members the brace plate is provided with a depending flange 14. There will be a brace plate 11 at each corner of the structure and it will be observed that the plates thus serve to firmly unite the base A and the front and side walls of the range to the brace plate. These parts are thus held in position for handling.
- I also utilize the screws 10 as means by which to connect and disconnect the legs 14' to the structure. Attention is directed to the fact that preferably the upper ends of the legs are provided with marginal vertically extending abutments 15 which form a recess to receive the brace plate 11, while the downwardly extending flange 14 on the brace plate 11 will fit against the inner edge 16 of the said legs. Located in this recess of the upper end of the leg are projections 17 that are in the plane below the upper edge of the abutments 15. Hence when the brace plate is in position, its upper face will be below the upper edge of the abutments 15 a distance substantially equal to the thickness of the flange 1 of the base A. Formed through the inwardly extending flange 18 of the leg 14' are openings 19 which are made sufficiently large to let the extended ends of the screws 10 pass freely through them. To the extended ends of the screws are applied thumb nuts 20 by means of which the legs can be readily attached and detached from the range structure.
- The front wall 4 has formed therein an opening 21 that will be of a size and shape to correspond with the size and shape of the door (not shown). This opening will be formed in the usual manner, that is by bending the lower edge 22 inward and out-side edges 23 also inward. Preferably its side edges are made wider than its bottom edge 22.
- Preferably in the construction shown I cut the horizontal flange 11 away as shown 70 at 23' a distance that will fit within the legs 15 formed on the top of the leg portion.
- In the construction here shown, I preferably extend the outer edges of the side walls 7 as shown at 24, the same being 75 pressed inward as shown at 25, whereby the flanges 24 rest on the inner side of the flange 6 of the front wall.
- It will be noted that the brace plate 11 has its edges cut angular to correspond with 80 the recess formed in the top of the legs and to permit the said plate portion to fit within the legs 5.
- I desire it to be understood that the construction herein shown and described may 85 be varied by those skilled in the art without departing from the spirit and scope of a fair interpretation of the appended claims.
- Having thus described my invention, 90 what I desire to claim and secure by Letters Patent is:
1. In a range construction, a base plate having an outwardly extending horizontal flange, side and front walls having their 95 lower edges bent inward to fit the said horizontal flange, and means for securing the flanges together, whereby the base is substantially concealed within the structure.
  2. A range structure having a base L 100 shaped in cross section, its horizontal portion extending outward, and side and front walls having inwardly bent flanges secured to the horizontal flange, whereby the base is concealed within the structure. 105
  3. A range structure comprising an L shaped base plate having its horizontal portion extending outward, side and top walls fitting thereon, their lower edges bent inward and fitting said horizontal flange and 110 a brace plate below the said base member, and means for securing all the parts together.
  4. A range structure having an L shaped base, its horizontal portion extending outward, front walls turned inward and fitting the said horizontal flange, and means for detachably securing the parts together. 115
  5. A horizontal range comprising an L shaped base portion having its horizontal 120 flange extending outwardly, front and side walls having their lower edges extending inwardly, a brace plate below the said horizontal flange and screw members passing through the said parts and holding them together. 125
  6. A range structure comprising an L shaped brace member having its horizontal flange extending outwardly, side and front walls having their lower edges extending 130

- inwardly, a brace plate below said horizontal flanges of the said members having registering openings, and the openings in the brace plate screw threaded and screws passing through the said openings and holding the parts together.
7. A range structure having an L shaped base, the horizontal portion extending outward, side and front walls with edges turned inwardly and fitting the horizontal flanges, a brace member below the horizontal flanges, screws passing through the horizontal flanges and extending therebeyond, leg portions having openings registering with the said screws and nuts fitting on the lower ends of the projecting screws whereby the said parts are detachably connected together.
8. A range structure comprising an L shaped base portion having its horizontal flange extending outwardly, side and front walls having their edges bent inwardly fitting the said horizontal flange, a brace plate below the said horizontal members, and a leg portion having its top recessed and receiving said brace member, the parts having registering openings and bolts passing through the said registering openings for connecting them together.
9. A range structure comprising an L shaped base portion having its horizontal flange extending outwardly, side and front walls having their lower edges extending inwardly, a brace member below the said horizontal flanges having its inner edge with a depending flange, a leg portion fitting the said brace, the parts having registering openings, and screws passing through the said registering openings and connecting the parts together.
10. A base members for ranges consisting of an L shaped bar, the horizontal portion cut outwardly and the base bent to form a shape corresponding to the shape of the range, and side and front walls with their inner edges bent inwardly, and means for connecting the horizontal flanges together.
11. A base for ranges comprising an L shaped member, the horizontal portion of the L shaped member cut outwardly, said base member bent at said cut to a shape corresponding to the shape of the range, front and side walls with their lower edges horizontally turned inwardly, and means for connecting the horizontal portions together.
12. A range structure having a base consisting of an L shaped member having the horizontal portion cut away leaving an uncut portion, said base being bent at a point midway between the side walls of the cut-out portion, thereby stretching the said metal, front and side walls having their lower edges turned horizontally inwardly and means for connecting the horizontal portions together.
13. A range structure having a base formed of an L-shaped member with its horizontal portion extending outwardly, said horizontal portion cut away forming a narrow portion that constitutes a reinforcing outwardly extending relatively narrow flange, side and front walls with their lower edges turned inwardly, and means for connecting the parts together.
14. In a range construction, a base, front and side walls having their lower edges turned inward and engaging the said base, a brace located under the base and securing means passing through the said inturned wall flanges and into the brace whereby the structure is united.
15. In a range construction, a base plate, front and side walls having their lower edges turned inward and fitting on the base plate, and a brace plate below the said base plate, and screws passing through the front and side wall inturned lower edges and base plate into the brace plate and securing the structure together.
- In testimony whereof I hereunto affix my signature.

JOSEPH ROY.
